C. H. PRESCOTT.

BOILER CLEANER

SOOTER CLEANER.

899,261.

Patented Sept. 22, 1908.

UNITED STATES PATENT OFFICE.

CHARLES H. PRESCOTT, OF EAST LIVERPOOL, OHIO.

BOILER-CLEANER.

No. 899,261.

Specification of Letters Patent.

Patented Sept. 22, 1908.

Application filed March 12, 1908. Serial No. 420,724.

To all whom it may concern:

Be it known that I, CHARLES H. PRESCOTT, citizen of the United States, residing at East Liverpool, in the county of Columbiana and 5 State of Ohio, have invented certain new and useful Improvements in Boiler-Cleaners, of which the following is a specification.

The present invention relates to certain new and useful improvements in boiler cleaners of that type in which the soot and other accumulations within the fire flues is blown out by means of a jet of live steam.

The object of the invention is to design a novel boiler cleaner which will operate in an 15 effective manner to clean the flues and which can be readily built into the wall of the boiler.

For a full description of the invention and the merits thereof and also to acquire a 20 knowledge of the details of construction and the means for effecting the result, reference is to be had to the following description and accompanying drawings, in which:

Figure 1 is a sectional view through a 25 boiler showing the cleaner applied thereto. Fig. 2 is an enlarged longitudinal sectional view through the cleaner. Fig. 3 is a transverse sectional view through a boiler having the cleaner applied thereto. Fig. 4 is an enlarged transverse sectional view through the 30 lateral arm of the cleaner.

Corresponding and like parts are referred to in the following description and indicated in all the views of the drawings by the same 35 reference characters.

Referring to the drawing, the numeral 1 designates a boiler which is of the horizontal type and is provided with the flues 2 through which the products of combustion pass. 40 Spaced from and located directly opposite one end of the boiler is a wall 3, and built in or otherwise suitably applied to this wall is a chest 4. This chest is preferably rectangular in cross section so as to be interposed between the various courses of brick work and one end of the chest projects outwardly beyond the wall and is provided upon its upper side with a boss 5 to which a steam pipe 6 is connected, and upon its lower side with a 45 drain cock 7. A packing gland 8 is located at the outer end of the chest and co-operates with a nut 9 to retain packing around a rod 10 which passes longitudinally through the chest. A handle 11 is applied to the outer 50 extremity of the rod 10 and constitutes a

means for rotating the rod and moving it longitudinally. In the present instance the handle is provided at its middle point with an angular socket 12 receiving an angular portion of the rod, the extremity of the rod 60 being threaded to receive a nut 13 which retains the handle securely in position upon the rod. A valve 14 is interposed in the length of the steam pipe 6 and a drain cock 15 for withdrawing the condensed steam is 65 located immediately over the said valve.

The inner end of the chest 4 is formed with an opening within which a sleeve 16 is threaded, the said sleeve projecting within the chest. Slidably mounted within the 70 sleeve 16 is a pipe 17 one end of which extends within the chest and has a collar 18 threaded upon the exterior thereof, the said collar being formed with a yoke 19 which is secured to the rod 10 and forms a connection 75 between the rod and the pipe. Carried by the opposite end of the pipe 17 is a laterally extending arm 20 provided at one end with a boss within which the extremity of the pipe 17 is threaded. This arm 20 gradually 80 tapers toward the free end thereof which is closed by a removable plug 21, such a construction permitting ready access to be had to the interior of the arm for cleaning the same. It will also be observed that the arm 85 20 is triangular in cross section and is provided along one of the longitudinal corners thereof with a plurality of openings 22 through which the steam is designed to issue in jets and pass through the boiler flues when 90 the device is in operation. With this construction it will be readily apparent that by suitably manipulating the handle 11 the lateral arm 20 can be moved back and forth between the wall 3 and the end of the boiler 95 and can be rotated so as to be brought into co-operative relation with all of the flues 2 passing through the boiler.

Attention may here be directed to the fact that owing to the manner of mounting the 100 chest 4 in the wall directly opposite the central portion of the upper row of flues a half-turn on both sides will cover all the tubes of the boiler. It will also be noted that when the lateral arm is moved toward the boiler 105 head the collar 18 abuts against the sleeve 16 and tends to prevent leakage of steam between the pipe and the sleeve.

When the cleaner is not in operation the 110 pipe 17 and lateral arm carried thereby are

2
drawn inwardly and the lateral arm permitted to rest upon the horizontal ledge 23 projecting from the inner face of the wall.

Having thus described the invention, what is claimed as new is:

1. The combination of a boiler provided with flues and having a wall opposite one end thereof, a chest mounted in the wall, a pipe extending loosely through the inner end of 10 the chest and communicating with the interior thereof, a steam pipe leading to the chest, a lateral arm carried by the pipe and having a triangular cross section, the end of the lateral arm being open, and one of the longitudinal edges of the said arm being formed 15 with a series of jet openings, a removable plug for the open end of the arm, and means for rotating the pipe to swing the lateral arm across the end of the boiler, so that the steam jets issuing therefrom will pass through the flues.
2. The combination of a boiler provided

with flues and having a wall opposite one end thereof, a rectangular steam chest mounted in the wall, a packing box at the outer end of 25 the steam chest, a sleeve projecting within the steam chest at the inner end thereof, a pipe passing loosely through the sleeve, a collar applied to the pipe and co-operating with the sleeve to limit the sliding movement of 30 the pipe, a yoke upon the collar, a rod extending through the packing box and having an operative connection with the yoke for rotating the pipe and moving the same longitudinally, and a lateral arm carried by the pipe 35 and adapted to be swung across the end of the boiler, the said lateral arm being formed with jet openings.

In testimony whereof I affix my signature in presence of two witnesses.

CHARLES H. PRESCOTT. [L. s.]
